(57) **CLAIM**

The ornamental design for a laser, as shown and described.

DESCRIPTION

FIG. 1 is a first perspective view of the laser of the present invention;

FIG. 2 is a left side view of the laser of FIG. 1

FIG. 3 is a right side view of the laser of FIG. 1;

FIG. 4 is a rear view of the laser of FIG. 1;

FIG. 5 is a front view of the laser of FIG. 1;

FIG. 6 is a top view of the laser of FIG. 1; and,

FIG. 7 is a bottom view of the laser of FIG. 1.

The broken lines in the Figures are for illustrative purposes only and form no part of the claimed invention.
